UNITED STATES PATENT OFFICE

IRVIN F. DITTMAR, OF WILLIAMSPORT, PENNSYLVANIA, ASSIGNOR TO THE CROMAR COMPANY, OF WILLIAMSPORT, PENNSYLVANIA, A CORPORATION OF PENNSYLVANIA

MACHINE FOR COATING STRIPS OF LUMBER

Original application filed September 13, 1924, Serial No. 737,528. Divided and this application filed May 16, 1925. Serial No. 30,736.

This invention relates to a machine for coating strips of lumber adapted to be used in connection with strip coating machines, such as disclosed in the application of Elmer C. Dittmar, filed July 31, 1919, Serial Numbers 314,464 to 314,467, renewed November 11, 1922, Serial Numbers 600,476 to 600,479, and is a divisional application of my application filed September 13, 1924, Serial Number

10 737,528, the object being to provide means for first cleaning and then tilting the strip of material after it has its face coated so that the strip of material will be deposited on the receiving table with clean edges and with its 15 coated face on top so as to prevent the marring of the finished face of the strip after it has passed through the machine.

Another and further object of the invention is to provide a coating machine wherein 20 a strip is brushed so as to remove any foreign particles from the edge of the strip after it leaves the guide way and before it reaches the tilting device.

Other and further objects and advantages 25 of the invention will be hereinafter set forth and the novel features thereof defined by the appended claims.

In the drawings,

Figure 1 is a side elevation of a finishing 30 machine showing the application of my improved construction of cleaning and tilting devices thereto;

Figure 2 is a side elevation of the delivery end of the machine showing the manner of 35 mounting the tilting and cleaning devices;

Figure 3 is a sectional view through the brush support;

Figure 4 is a detail elevation of the support for the tilting roller;

Figure 5 is an edge view of the same;

Figure 6 is a vertical section through the supporting roll;

Figure 7 is a detail view of the tilting roll showing the manner of mounting the same; 40 and

Figure 8 is a detail elevation of the back-up roll.

In the drawings 1 indicates a frame of a strip coating machine upon which is mounted 45 a guideway 2 formed of tracks adjustably

supported through which a strip of material to be finished is adapted to be forced by feed rollers 3 movably mounted so as to be adjusted towards and away from the strip in order to allow the rollers to be moved into and out of contact with the strip in order to move the strip and stop the movement thereof, the feed rollers being driven by suitable driving mechanism as clearly shown which forms no part of this invention. 55

The strip is coated in its passage through the machine by a coating receptacle 5, constructed substantially in the same manner as disclosed in the applications of Elmer C. Dittmar above referred to and is then burnished by a rotary burnishing device 6 driven by suitable driving means, the succeeding strip serving the purpose to force out the preceding strip so that strips of material are fed continuously through the machine on edge 60 and are finished in their passage therethrough, the above description being given so that the operation of my improved construction of cleaning and tilting device when applied to a machine of this nature can be 65 readily understood.

It is, of course, understood that I do not wish to limit myself to the application of my improved construction of cleaning and tilting device to any particular construction of coating machine as I am aware that with various changes, the cleaning and tilting device can be applied to various forms of coating machines in which a strip of material is moved continuously therethrough without departing 70 from the spirit of my invention.

Secured to the frame 1 or bed of the machine at the delivery end thereof is an angular post 7 extending outwardly beyond the end of the guideway as clearly shown for the 75 purpose hereinafter specified.

Carried by the post 7 is a block 8 provided with an eccentric pin 9 on which is mounted a back-up roller 10 adapted to engage the back of a strip in its passage through the guideway, said roller being adjusted and set so as to engage the back of the strip as it passes through the guideway. Fixed on the post 7 is a block 11 provided with a slot in which is adjustably mounted a stud shaft 12 80

capable of being adjusted vertically by a screw 13, the end of the stud shaft being provided with a head 14, over which is revolvably mounted a hub 15, said stud being provided with an oil passage 16 for feeding lubricant to the hub 15.

Secured to the end of the hub is an idle roller 17, the periphery of which is preferably formed V-shape in cross section and is adapted to fit within the V groove of the strip of material in its passage over the same.

In the embodiment of my invention as herein shown, I have illustrated and described the tilting and cleaning device especially adapted to be used in connection with a finishing machine for coating a strip of flooring which has a V-shaped groove along one edge and a V-shaped tongue along its other edge and the cooperating parts are formed this shape so as to support the strip after it leaves the guideway.

It is, of course, understood that I do not wish to limit myself to an idle supporting roller with any particular construction of periphery as the shape of the periphery will be changed to correspond to the edge of the strip of material which it engages and supports.

The upper end of the post 7 is turned back upon itself and has a bore formed through the aligning parts thereof in which is mounted an oscillating shaft 19 locked in position therein by a key 20 for preventing endwise movement, the oscillating shaft being provided with a transverse bore 21 intersected by a threaded bore 22 in which is mounted a thumb screw 23 for the purpose hereinafter fully described.

Extending through the transverse bore 21 of the oscillating shaft 19 is a lever arm 24 carrying a revolvably mounted tilting roller 25 adapted to bear on the upper edge of the strip of material in its passage through the machine so as to tilt the strip on the supporting or idle roll 17 so as to cause the strip of material to be delivered on the receiving table with its coated face up, thereby preventing the finished face of the strip from being marred or injured in any way in being delivered from the machine.

The face of the tilting roller 25 is maintained clean by a pivoted lever 26 carrying a scraper 27 which has a shearing action on the face of the tilting roller, the construction and operation of the tilting roller being clearly illustrated in my companion application.

In this embodiment of my invention, the position of the tilting roller and supporting roller is such that a pair of brushes 28 and 29 can be placed beyond the end of the guideway between said end and the tilting roller and these brushes are adapted to be driven by belts 30 and 31 from a driving shaft of the machine so that the edges of the strip will be cleaned before it reaches the tilting device,

said brushes being adapted to rotate in a reverse direction to the movement of the strip.

The brushes 28 and 29 are carried by shafts 32 and 33 mounted in bearings formed on the ends of lever arms 34 and 35 as clearly shown. 70 The brush supports or bearing arms are mounted on bearings carried by a post 36 extending from the bed alongside of the guideway and to which the guideway is secured. The brushes are adjusted by links 37 and 38 working through an angle plate 39 carried by the post 36, the ends of the links being threaded and having handles screwed thereon so that on the turning of the handles, the brushes can be adjusted up and down so as to adjust the position of the brushes in respect to the strip of material passing therethrough and to compensate for the wear on the brushes when in use.

This particular construction of mounting 85 the brushes on lever arms and having the same capable of being adjusted up and down provides a novel means for mounting the brushes and for adjusting the same without interfering with the rotation of the brushes, the brush shafts being provided with pulleys 90 over which the drive belts pass so as to rotate these brushes in the opposite direction to the strip of material whereby the edges of the strips are thoroughly cleaned as they leave 95 the guideway so that when the strip reaches the tilting roll it is clean, thereby preventing the tilting roll from forcing any foreign matter over on the face of the strip.

From the foregoing description it will be 100 seen that I have provided a cleaning device for finishing machines wherein a pair of brushes are disposed at the delivery end of the machine so that the strip delivered therefrom is cleaned before it reaches the tilting 105 roll whereby I am able to coat and finish strips of lumber and deliver the strips of lumber onto a receiving table in perfect condition.

While in the drawing and specification I 110 have shown and described a tilting and cleaning device especially adapted to be used in connection with a coating machine, it is, of course, understood that the tilting and cleaning device can be used in connection with 115 other machines, such as the Yates Miller or any other machine where it is desired to have the strip delivered from the machine with one face upmost and therefore I do not wish to limit myself to the use of my improved 120 construction to any particular kind of machine.

What I claim is:

1. The combination with a machine of the kind described having means for guiding and propelling a strip on edge in its passage therethrough, of a pair of lever arms mounted on the machine carrying bearings at their free ends, shafts mounted in said bearings carrying brushes, means for revolving said 130

shafts and means for moving said lever arms and holding the same in adjusted position.

2. A machine of the kind described having means for guiding and propelling a strip on edge in its passage therethrough, of a pair of lever arms carrying rotary brushes arranged to engage a strip in its passage therethrough, links connected to said lever arms provided with threaded ends and handles 10 provided with threaded sockets to receive the threaded ends of said links for adjusting said brushes in respect to the guiding means of said machine.

3. A machine of the kind described having 15 means for guiding and propelling a strip of lumber in its passage therethrough, of a pair of lever arms mounted on the machine at the delivery end thereof, rotary shafts mounted in said lever arms, brushes carried by said 20 shafts, belts for driving said shafts and means for adjusting the position of said lever arms.

In testimony whereof I hereunto affix my signature.

25 IRVIN F. DITTMAR.
